Inventor:

W. B. Coates.

United States Patent Office.

WILLIAM B. COATES, OF PHILADELPHIA, PENNSYLVANIA.

Letters Patent No. 80,455, dated July 28, 1868.

IMPROVEMENT IN FIREPLACES.

The Schedule referred to in these Letters Patent and making part of the same.

TO ALL WHOM IT MAY CONCERN:

Be it known that I, WILLIAM B. COATES, of the city of Philadelphia, county of Philadelphia, and State of Pennsylvania, have invented an Improved Stove; and I hereby declare the following to be an exact description thereof, reference being had to the accompanying drawings, and to the letters of reference marked thereon, making a part of this specification, in which—

Figure 1 represents a front view of the stove, with its self-acting ash-sifter below.

Figure 2 is a vertical section of the stove.

Figure 3 represents a side elevation of same.

Figure 4 represents a cross-section of the ash-sifter.

Figure 5 represents a top view of the convex-shaped grate.

Figure 6 represents a side view of the grate, with its shaker and the lower plate in which it revolves.

Figure 7 represents an under side view of the stove and grate-plate, with their flanges, and apertures for discharging the ashes.

The nature of my invention consists in the construction of the stove, with its ribbed conical top, its doors sliding on each side of the stove, and a convex-shaped grate, with flange, operating on the inside of the flanges of the bed-plate of the stove, vibrated by a peculiarly-shaped shaker.

Underneath the bottom of the stove is a self-acting sifter, that is located in the cellar or under the floor of the fireplace upon which the stove stands, the sifter having discharge-pipes at its end, the coarse ashes falling through the front one, and the dust through the under one.

At the rear part, and outside of the stove, is attached a receptacle for water, with two upright pipes, one having a swivel top, through which the water is poured into the receptacle, the other to carry off the steam into the flues.

The stove has a double-jointed pipe, leading into the lower side of an oval-shaped drum, with a pipe at the top to carry off the smoke into the chimney.

Fig. 1 represents the front of the upright stove, with a fire-board, A, surrounding it, that is used when the stove is set into a fireplace.

B is the ribbed conical top of the stove, is made of cast iron, and fitted upon the top, 'C, of the body of the stove.

D D are the sliding doors, that slide from front to the back, around the body of the stove, and, when open, leave one-half of the stove open, so as to form an open grate. The top edge of each door D is angular, and operates in an angular groove in the lower edge of the body C of the stove. The lower edges of the doors D have angular grooves resting upon the sharp edge, and operating on the cylinder E below, so as to enable the doors to work freely, and not be choked up by ashes collecting on the edges of the cylinder. The front of one door D has a rounding bead on the outer edge, to make a close joint when the doors are closed.

F represents the handle of the shaker, that passes through the cylinder of the stove, and has an elbow or arm, G, extending downwards, with a round knob at its lower end, that catches into the front part of the rim H of the grate I, by which means the grate is vibrated back and forwards.

The rim H (on which the convex grate I rests and operates) fits upon the lower bed-plate J, and has a flange, K, on its lower side, that revolves on the inner side of a flange, L, on the bed-plate J of the stove.

The bed-plate J has semicircular apertures, M, through which the ashes are discharged into the funnel N beneath, that conducts the ashes to the inclined sifter O, that has a grate, P, through its centre, by means of which the coarse ashes or coal are carried off through the spout Q, and the dust, as the ashes pass through the sifter O, falls through the grate P, and passes down through a spout into receptacle R, by which means the ashes are thoroughly sifted, and the sifter O, being covered with a sliding lid, prevents the dust from escaping or being scattered about while it is passing down into the receptacle R, whilst the coarse ashes continually pass down the upper side of the grate P, (on account of the momentum of the fall at the upper end, and the incli-

(vibration of the grate.) The coal is all saved and collected without making dust or dirt, as is usually the case with other sifting-machines.

S is a draught-pipe under the floor, through which cold air may be passed up into the stove. T is a receptacle for water at the lower side of the stove, with two upright pipes, U U, for the purpose of distributing moisture or steam through the room or upper flues.

The front pipe U has a swivel-neck and stopper at the top, through which water can be introduced at any time to fill the reservoir, or (when necessary) discharges moisture into the room by removing the stopper at the top.

The smoke passes off from the stove through the double-jointed pipe V, that is connected at the lower side of a drum or heater, W, and passes off through smoke-pipe X, thereby increasing the draught more than is usual with ordinary heaters.

The body of the stove C, at Y, rests in an offset or shoulder on the top of the cylinder E, as shown in fig. 2, the inside of the cylinder E being convex at the centre, and thicker than at the top or bottom, thereby preventing the cylinder from burning out as soon as it would otherwise do, and having feet, Z, on each side at the bottom, for fastening the cylinder to the bed-plate.

What I claim as my invention, and desire to secure by Letters Patent, is—

1. The combination of the vibrating-rim H, with its flange K, and the bed-plate J, with its flange L and apertures M, the shaker F, with its arm G and knob, as herein described and for the purposes set forth.
2. The construction of the body of the stove, when combined with the cylinder E, shoulder Y, and ribbed top B, as herein described.
3. In combination with the foregoing the sifter O, with funnel-shaped top, N, grate P, spout Q, and receptacle R, when constructed and operating as herein described and for the purpose set forth.

WILLIAM B. COATES.
